[57] **CLAIM**

The ornamental design for a bag holder, as shown and described.

DESCRIPTION

FIG. 1 is a front perspective view of the bag holder of my new design;

FIG. 2 is a reduced scale front elevational view of the bag holder of FIG. 1;

FIG. 3 is a side elevational view of the right side of FIG. 2, the opposite side being a mirror image thereof;

FIG. 4 is a top plan view of FIG. 2;

FIG. 5 is a bottom plan view of FIG. 2; and,

FIG. 6 is a rear elevational view of FIG. 2.
